(57) **CLAIM**

The ornamental design for a gyroplane, as shown and described.

DESCRIPTION

1. Gyroplane

1.1 is a top, front, and left side perspective view of a gyroplane embodying my new design;

1.2 is a front elevation view thereof;

1.3 is a rear elevation view thereof;

1.4 is a top plan view thereof;

1.5 is a bottom plan view thereof;

1.6 is a left side elevation view thereof; and

1.7 is a right side elevation view thereof.

3.1 is a top, front, and left side perspective view of a gyroplane embodying my new design in accordance with an alternate embodiment;

3.2 is a front elevation view thereof;

3.3 is a rear elevation view thereof;

3.4 is a top plan view thereof;

3.5 is a bottom plan view thereof;

3.6 is a left side elevation view thereof; and

3.7 is a right side elevation view thereof.

The broken lines in the reproductions illustrate portions of the gyroplane that form no part of the claimed design.
